UNITED STATES PATENT OFFICE.

WILLIAM C. LAMBETH, OF HENDERSON, TEXAS.

PEANUT-SHELLER.

1,258,125.

Specification of Letters Patent.

Patented Mar. 5, 1918.

Application filed October 3, 1917. Serial No. 194,543.

To all whom it may concern:

Be it known that I, WILLIAM CARL LAMBETH, a citizen of the United States, residing at Henderson, in the county of Rusk, State of Texas, have invented certain new and useful Improvements in Peanut-Shellers; and I do hereby declare the following to be a full, clear, and exact description of the invention, such as will enable others skilled in the art to which it appertains to make and use the same.

This invention relates to improvements in shelling machines and particularly to peanut shelling machines.

One object of the present invention is to provide a peanut shelling machine which can be used in the home to shell large or small quantities of peanuts.

Another object is to provide a device of this character which is simple and cheap in its construction and which can be easily and effectively operated.

A further object is to provide a device of this character which will shell a larger quantity of peanuts in a given space and with a given amount of energy and time, than with similar devices heretofore.

Other objects and advantages will be apparent from the following description when taken in connection with the accompanying drawing.

In the drawing:

Figure 1 is a side elevation of a peanut sheller made in accordance with my invention.

Fig. 2 is an end elevation of the same.

Fig. 3 is a vertical sectional view taken on the line 3—3 of Fig. 1.

Fig. 4 is a vertical longitudinal sectional view taken on the line 4—4 of Fig. 2.

Fig. 5 is a horizontal sectional view taken on the line 5—5 of Fig. 1.

Fig. 6 is a bottom plan view of the device, partly broken away.

Referring particularly to the accompanying drawing, 10 represents a cylindrical casing through which extends a central horizontal shaft 11. In the upper side of the casing there is formed an opening 12 through which the peanuts are fed to the interior of the casing. A hopper 13 is carried over this opening to hold the quantity of peanuts which are fed to the casing. In the center of the lower side of the casing 55 there is formed an outlet spout 14 for the

discharge of the shelled peanuts and the shells thereof.

On one end of the shaft, outwardly of the end of the casing, there is attached a crank handle 11' by means of which the shaft is arranged to be rotated. Secured on the shaft, within the casing, are two disks 15, each of which is formed with a plurality of radiating slots 16, of constant width throughout their entire lengths. These disks are spaced approximately two inches apart on the shaft, and at slightly less distances from the end walls of the casing. These end walls of the casing have their inner faces formed with ribs 17 for co-operation with the walls of the slots 16 to cause the effective breaking of the shells of the peanuts as the disks are turned by the crank handle. It will be noted that the edges of the disks are spaced from the inner face of the curved wall of the casing a sufficient distance to permit the broken shells and kernels of the peanuts to readily pass therethrough, but not large enough to permit the unshelled peanuts to pass.

In the upper portion of the casing, immediately below the inlet opening of the hopper, there is secured a curved guard plate 18 which covers the upper portions of the peripheries of the disks and prevents the passage of the peanuts between the disks, and forces them to pass between the outer faces of the disks and the end walls of the casing.

Thus as the crank handle is turned the peanut shells will be effectively broken between the walls of the slots 16 and the ribs of the end walls of the casing, the broken shells and the kernels passing through the said slots and being discharged through the outlet spout into any suitable container placed therebeneath.

The casing is provided with a clamp 19 by means of which the device may be secured to the edge of a table or other like support.

There is thus provided a simple peanut sheller which can be used in the home and which can be readily operated by anyone, thereby obviating the use of large machines and the cost of buying the shelled peanuts.

What is claimed is:

1. A peanut sheller including a casing, a hopper carried by the upper portion of the casing, a discharge spout carried by the

lower central portion of the casing, a longitudinal shaft mounted in the casing and having a crank handle on one end, a pair of spaced disks mounted on and rotatable with the shaft, said disks being formed with radial slots constant in width throughout their lengths, said casing having its end walls formed for coöperation with the outer faces of the disks and the walls of the slots thereof for crushing the shells of peanuts, and a curved guard plate mounted above the space between the disks, said disks being spaced from the curved walls of the casing.

2. A peanut sheller including a casing, a hopper mounted on the casing and communicating with the interior thereof, stationary crushing elements mounted in the casing, spaced rotary crushing elements mounted in the casing and provided with openings for the passage of the crushed shells and kernels of the peanuts therethrough, stationary means for directing the uncrushed peanuts between the rotary elements and the stationary elements, and means for delivering the crushed shells and kernels from the space between the rotary elements.

3. A peanut sheller including a casing having a feeding opening in the top thereof, stationary crushing elements in the casing, rotary crushing elements mounted within the casing below said feeding opening and spaced from the stationary elements and from each other, said rotary elements coöperating with the stationary elements to crush the shells of the peanuts therebetween, said rotary elements being provided with openings to permit the passage of the crushed shells and kernels into the space between said elements, a discharge spout located below the said space, and a stationary guard disposed in the said feeding opening in position to direct the unshelled peanuts between the rotary and stationary elements and to prevent the passage of the unshelled peanuts into the space between the rotary elements.

In testimony whereof, I affix my signature in the presence of two witnesses.

WILLIAM C. LAMBETH.
